E. M. FOSTER,
DEMOUNTABLE RIM OPERATING LEVER,
APPLICATION FILED JULY 15, 1918.

1,394,989.

Patented Oct. 25, 1921.

UNITED STATES PATENT OFFICE.

EMORY M. FOSTER, OF CLEVELAND, OHIO, ASSIGNOR TO THE HYDRAULIC PRESSED STEEL COMPANY, OF CLEVELAND, OHIO, A CORPORATION OF OHIO.

DEMOUNTABLE-RIM-OPERATING LEVER.

1,394,989.

Specification of Letters Patent.

Patented Oct. 25, 1921.

Application filed July 15, 1918. Serial No. 244,951.

To all whom it may concern:

Be it known that I, EMORY M. FOSTER, a citizen of the United States, residing at Cleveland, in the county of Cuyahoga and State of Ohio, have invented a certain new and useful Improvement in Demountable-Rim-Operating Levers, of which the following is a full, clear, and exact description, reference being had to the accompanying drawings:

This invention relates to a novel construction of tool for opening and closing transplit demountable tire carrying rims.

The object of the invention is to combine an exceedingly simple and highly efficient construction of operating tool which can be utilized for opening or contracting the rim and also serving as a lock to hold the rim in such opened or contracted position.

20 The tool is particularly adapted for use in connection with the type of demountable rim shown and described in Patent No. 1,299,451, dated April 8, 1919.

The invention consists in the novel features of construction hereinafter fully described and set forth in the appended claims.

In the drawings forming a part of this specification Figure 1 is a perspective view showing the meeting ends of a transplit demountable carrying rim together with my improved construction of operating lever connected thereto. Fig. 2 is a similar view showing the tool in course of operation, the dotted lines indicating the final or locked position and Fig. 3 is a detail perspective view of the tool, the parts thereof being disconnected.

Referring to drawings A indicates one end of the transplit tire carrying rim, and B the opposite end thereof. A lug or member C is attached to the rim end A some distance from the extreme end thereof and a block or member D is attached to the end B, this block D extending slightly beyond the extreme end of the part B.

The lug or member C has a transverse bore or opening C' produced therein and the block or member D has a transverse bore or opening D' produced therein, the opening C' being nearer to the center of the rim than the opening D'.

The operating tool comprises a plate-like head portion E, and a handle portion F, the handle portion having a socket F' produced in the angled end thereof, this socket being

adapted to receive the angled end E' of the head portion E. The plate-like head portion is provided with a laterally projecting pin or stud G adjacent to one end, and a similar pin or stud H adjacent to the angled end, and in operation the pin or stud G is inserted in the block C while the pin or stud H is inserted in the block D. This placement of the head in connection with the blocks or as the head in connection with the blocks or as lugs of the rim is usually accomplished while the handle is removed from the head. The handle is then connected to the head by placing the socket thereof over the angled end of the head and then, by turning the lever as a whole upon the pin or stud G as a fulcrum, the end B of the transplit rim will first be separated slightly from the end A and caused to move inwardly and over the end portion A.

During the first portion of this movement the lever is acting against the resiliency of the sheet metal rim, but the moment the pin or stud H passes beyond the radial line passing through the pin or stud G, the resiliency of this rim will tend to aid the lever in the opening operation, and the contracting operation will continue until the head has swung entirely over; and in order to permit the full movement of the lever head, one face thereof is cut out as shown at I to receive the base of the rim end B, and when the rim has been thus contracted it will be held locked in such contracted position and the handle portion F can be removed from the head, the head remaining in locked relation with the rim ends.

The rim having been thus contracted, the tire can be quickly and easily removed therefrom or placed thereon, as it will be seen that a considerable contraction of the rim has been accomplished. The distance between the pins or studs G and H is approximately two inches, and consequently, the total amount of contraction of the rim will amount to approximately four inches, and this will always be ample to permit the tire to be quickly and easily removed therefrom or placed thereon.

When it is desired to restore the rim to its normal, closed and true circular shape, the handle is once more connected to the lever head and the lever is swung back on the pin or stud G as a pivot or fulcrum once more, and during the first half of its movement

it is operating against the resiliency of the rim, but during the latter half of its movement the resiliency of the rim is acting with the force of the lever and the ends 5 A and B will be brought down in the position shown in Fig. 1, and the lever can then be disconnected entirely from the rim.

The head portion of the lever serves as a lock to hold the parts in their contracted 10 positions when the rim has been contracted to its full extent, the base of the rim fitting into the reentrant angle or notch produced in one edge of the plate-like head.

When the rim has been contracted to the 15 full extent and the handle removed from the head, the extreme end of said handle can be used as a tire tool, if so desired.

Having thus described my invention, what I claim is:

20 1. A device of the kind described comprising a head portion having a notch in one side thereof, and provided with spaced lat-

erally projecting studs, and a handle detachably connected to said head portion.

2. A device of the kind described comprising a plate angled at one end, and having spaced laterally projecting studs, said studs projecting away from the angled end portion, one edge of said plate between said studs being reentrant, and a handle portion 30 having a socketed angled end adapted to receive the angled end of said plate.

3. A tool of the kind described comprising a handle portion having a socket at one end, said socketed portion being arranged at 35 an angle to the main portion of said handle, and a plate having one end bent at an angle adapted to fit into said socketed end of the handle, said plate having spaced laterally projecting studs, the edge of said plate between said studs being notched or cut away.

In testimony whereof, I hereunto affix my signature.

EMORY M. FOSTER.
